YARN MARKER ATTACHMENT FOR
TEXTILE MACHINESGeorge B. McCombs, Magnolia, Miss., assignor of
one-half to R. L. Fuller, Magnolia, Miss.

Application June 12, 1941, Serial No. 397,807

10 Claims.

(Cl. 28—28)

This invention relates to an attachment for textile machines and more particularly to a device for marking the warp, while passing through the slasher with a piece of tape so that the tape will engage a part of the attachment, applied to a loom, for stopping the loom when the portion of the warp carrying the tape reaches a certain point in the loom, thus eliminating the necessity of having the warp constantly watched while passing through the loom, so that the loom will be stopped when a cut mark on the warp reaches a certain point in the loom.

It is important that the cut marks show on each end of a roll of cloth to insure that the cuts are taken off at uniform and specified lengths, not only to satisfy the buyer of the cloth, but also to afford a check on every yard of cloth woven, to insure that no cloth has been destroyed or stolen from either end of the roll. Where cut marks are not provided, employees frequently tear off cloth from the ends of a roll for use for towels, aprons and other purposes and this cannot be checked to prevent it without the use of a cut marking system, and unless checked creates a very large loss. However, it is very difficult and practically impossible for weavers to watch for the cut marks, due to the large number of looms which each weaver looks after and consequently many mills have abandoned the cut marking system for this reason.

It is therefore a primary aim of this invention to provide an improvement in the cut marking system which will operate automatically to apply an object to the warp, while passing through the slasher, which object will engage means carried by the loom for stopping the loom automatically as the portion of the warp, carrying the object, passes through the loom.

More particularly, it is an aim of the invention to provide an attachment including a device mounted on the slasher and actuated by the cut marker shaft thereof for cutting a piece of tape, from a roll of tape, and applying the cut piece to the warp, and thereafter advancing the tape to position another, uncut portion of the tape into position ready to have a portion thereof cut therefrom.

Still a further aim of the invention is to provide a feeler member adapted to be connected to a drop wire of the stop mechanism of the loom to be engaged and actuated by the tape while passing with the warp through the loom, for releasing said drop wire to permit it to move to a position for actuating the stop mechanism for stopping the loom.

Other objects and advantages of the invention will hereinafter become more fully apparent from the following description of the drawings, which illustrate a preferred embodiment of the invention, and wherein:

- Figure 1 is a fragmentary side elevational view showing a portion of one side of a conventional slasher with the tape marking attachment applied thereto,
10. Figure 2 is a fragmentary end view in elevation of the same looking toward the left hand end of Figure 1,
- Figure 3 is an enlarged cross sectional view taken substantially along the plane of the line 15. 3—3 of Figure 1,
- Figure 4 is a plan view of a portion of the warp with the tape applied thereto,
- Figure 5 is a perspective view of the feeler device, which is mounted on the loom and which 20 is actuated by the tape on the warp for stopping the loom,
- Figure 6 is an enlarged side elevational view of the mechanism for applying the tape to the warp, while passing through the slasher,
25. Figure 7 is a top plan view of the same.
- Figure 8 is a cross sectional view taken substantially along the plane of the line 8—8 of Figure 6,
- Figure 9 is a longitudinal vertical sectional view taken substantially along the plane of the line 9—9 of Figure 7, and
- Figures 10 and 11 are cross sectional views taken substantially along the planes of the lines 10—10 and 11—11, respectively, of Fig. 6.
35. Referring more particularly to the drawings, wherein like reference characters designate like or corresponding parts throughout the different views, 12 designates generally a portion of the entrance end of a conventional slasher, including a portion of a side member 13 of the slasher frame, a portion of the cut marker shaft 14, which is connected by gears, not shown, to the delivery roll 15, at the front or entrance end of the slasher. These parts are of conventional construction and are illustrated and described merely to better illustrate the application of the invention, designated generally 16. The attachment 16 includes a portion, designated generally 17, which is associated with the slasher 12, and 40 which includes a frame 18, the base 19 of which is disposed above and adjacent the warp 20 and near the delivery roll 15, as best seen in Figure 1.
45. Referring particularly to Figures 6 to 11, the frame 18 is provided at one end thereof with uprights 21 which form the ends of a U-shaped

member 22, the intermediate portion of which is fastened to the upper side of the base 19 by fastenings 23, as seen in Figure 9. A roll of adhesive tape 24 is disposed between the uprights 21 and is mounted on a shaft 25 which extends outwardly through said uprights and which is provided with a head 26 at one end thereof. A coil spring, of the expansion type, 27, is mounted on the shaft 25, and has one end bearing against the head 26 and its opposite end bearing against the adjacent side of the roll of tape 24. The upright 21 through which the spring 27 extends, is provided with an enlarged opening 28 for accommodating the spring, and the other upright 21 is provided with a smaller opening 29 in which a portion of the shaft 25 is journaled. A nut and washer, forming abutment means 30 are adjustably mounted on the opposite, threaded end of the shaft 25 to form a stop for an expansion coil spring 31 which is mounted on the shaft and which also bears against the outer side of the last mentioned upright 21 to combine with the spring 27 to resist the rotation of the roll of tape 24, for a purpose which will hereinafter become apparent.

The base 19 is provided with upright bearing stands 32, adjacent its opposite end, having base portions which are connected to the base 19 by additional fastenings 23. The bearing stands 32 are disposed in transversely spaced relationship to one another and are provided with aligned openings 33 in which a shaft 34 is journaled. A roller 35 is keyed to the shaft 34 and disposed between the bearing stands 32. The roller 35 is provided with an outer, rim portion 36 of felt or the like.

A roller 37 is disposed between the uprights 32 and above the roller 35 and has stub shafts 38 projecting from its ends and provided with bushings 39. The stub shafts 38 and the bushings 39, carried thereby, extend into vertically elongated openings 40 in the bearing stands 32 which are provided to permit the roller 37 to be moved upwardly and downwardly or toward and away from the roller 35. The bearing stands 32 are provided at their upper ends with perpendicular threaded openings 41 for receiving set screws 42 which bear against the bushings 39 to hold the roller 37 in engagement with the periphery of the roller 35.

The base 19, intermediate of its ends, is provided with an opening 43 in which is secured the lower end of a standard 44 which projects upwardly therefrom and which is provided with a longitudinal bore 45 extending therethrough. As seen in Figure 10, the standard 44 is also provided with a horizontal opening 46 which extends therethrough, lengthwise of the frame 18 and which is substantially wider than the bore 45. The bore 45 extends centrally through the opening 46. The standard 44, above the opening 46, is provided with perpendicular slots 47 which open into the bore 45 and outwardly of the sides of the standard 44 transversely of the frame 18. The standard 44 is secured to the base 19 by angular brackets 48 and a head 49 is mounted on the upper end of the standard 44 and secured thereto by brackets 50, having offset ends, as best seen in Figure 10. The head 49 is provided with a bore 51 which aligns with the bore 45. A solenoid 52 is mounted on the head 49 with the bore 53 thereof registering with the bore 51. The lower end of the solenoid 52 seats in a recess formed by lugs 54 which project upwardly from the head 49 and the solenoid is retained in posi-

tion on the head by means of detachable strap members 55, which are formed of metal, and which are fastened at the lower end of the head 49 and which are provided with inturned upper ends which engage against the upper side of the solenoid 52.

A core 56 of the solenoid 52 is slidably mounted in the bores 45, 51 and 53 and is formed of sections connected, as seen at 57, in end to end relationship. The lower section of the core 56 has a rectangular cutter 58 at its lower end. A rod 59 extends transversely through the lower section of the core 56. The ends of the rod 59 project outwardly through the slots 47 and are attached to the lower ends of contractile coil springs 60, the upper ends of which are attached to fastenings 61 in the head 49 for normally holding the core 56 in a raised position, as seen in Figures 6, 9 and 10.

Between the member 22 and the standard 44, the base 19 is provided with an opening or recess 62 in which is disposed a receptacle 63 which is adapted to contain water and which is provided with an opening 64 in the top thereof, and adjacent the standard 44. A roller 65 is journaled in the receptacle 63 and projects slightly through the opening 64. A rod 66 extends over the top of the receptacle 63, adjacent the roller 65, and between the roller and the member 22. As best seen in Figure 9, the free end of the tape of the roll 24 is passed under the rod 66, over the roller 65, through the opening 46, under and partly around the roller 35, and is wound on the roller 37. As seen in Figure 10, the width of the tape 24 is substantially equal to the width of the opening 46 and substantially greater than the lateral width of the core 56. The under side of the tape 24 is coated with an adhesive, not shown, so that in passing over the roller 65, which is rotated by frictional engagement therewith, it will be moistened due to the fact that the lower portion of the roller extends into the water, not shown, in the receptacle 63.

A shaft 67 is provided with a head 68, at one end thereof, which is secured to the outer side of one of the bearing stands 32. A gear 69 is journaled on the inner end of the shaft 67 and a ratchet wheel 70, which is fixed to the gear 69, is journaled on the intermediate portion of the shaft 67. A lever 71 is pivotally mounted intermediate of its ends on the shaft 67, on the outer side of the ratchet wheel 70. The parts carried by the shaft 67 are detachably retained in positions thereon by means of a removable collar 72 which is secured to the outer end thereof by means of a set screw 73. As seen in Figure 6, the teeth of the ratchet wheel 70 are all curved or inclined in a counterclockwise direction. A spring pressed pawl 74 is pivotally connected to the inner end of the lever 71, or to the end thereof adjacent to the standard 44 and is disposed to engage the teeth of the ratchet wheel 70, so as to turn the ratchet wheel when the lever 71 is swung in a clockwise direction, as seen in Figure 6, and to ride over the teeth of the ratchet wheel when the lever 71 is swung in a counterclockwise direction. As best seen in Figure 7, the head 68 is extended in a direction away from the pawl 74 and a spring pressed dog 75 is pivotally connected to the free end of the head 68 and has its free end disposed to engage selectively in the teeth of the ratchet wheel 70 to prevent the ratchet wheel from turning in a counterclockwise direction when the lever 71 is thus turned. Likewise, the dog 75 is yieldably mount-

ed to ride over the outer sides of the teeth of the ratchet wheel 70 when it is being turned in a clockwise direction. As seen in Figure 11, a pinion 76 is keyed to one end of the shaft 34 and disposed to mesh with the gear 69 for turning the roller 35 in a counterclockwise direction when the gear 69 and ratchet wheel 70 are turned in a clockwise direction for drawing the tape 24 from the roll which is disposed between the uprights 21.

The frame 18 may be supported in any suitable manner, as by means of a bracket 77, as seen in Figures 1 and 2, which is attached to the top of the side 13.

As seen in Figures 1 and 2, a cam 78 is secured by means of a set screw 79 to the cut marker shaft 14. A shaft 80 is disposed above the level of the shaft 14 and is journaled in bearings 81, which are attached to the side 13. A lever 82 is provided with a sleeve portion at one end thereof which engages the shaft 80 near one of its ends, and a lever 83 is provided with a similar sleeve portion at one end thereof which engages the shaft 80, near its opposite end. Set screws 84 are provided for adjustably keying the levers 82 and 83 to the shaft 80. The cut marker shaft 14 and the cam 78 turn in a counterclockwise direction, as seen in Figure 2, or in a direction as indicated by the arrow 85, in Figure 1, and the free end of the lever 84 is disposed to be engaged by the cam 78. The lever 82 is provided with a longitudinal slot 86, at its opposite, upper end through which extends the threaded end of a link or connecting rod 87. Said threaded end is provided with nuts 88, which are disposed one on either side of the upper end of the lever 82 for adjustably connecting the rod 87 thereto. The nuts 88 are disposed sufficiently loose so that the threaded end of the link or rod 87 can slide relatively to the slot 86. The opposite end of the connecting rod 87 is pivotally connected to the end of the lever 71, opposite to the end thereof which is provided with the pawl 74 and which end is normally disposed below the horizontal axis of the shaft 67, as best seen in Figure 2. A contractile coil spring 89 is attached at one end to the lever 82, adjacent its upper end and is anchored to the side 13, at its opposite end, for urging the lever 82 to swing toward the frame 18 for turning the lever 71 in a clockwise direction, as seen in Figures 2 and 6. It will thus be apparent that a push will be exerted on the connecting rod 87 by the action of the spring 89 while a pull will be exerted thereon by the action of the cam 78 rocking the lever 83 in a clockwise direction, as seen in Figure 2, to thereby rock the shaft 80 and the lever 82 in a clockwise direction.

A switch 90 is mounted above the cut marker shaft 14 by means of a bracket 91 which is secured to and depends from the member 13. An electrical conductor wire 92 leads from a source of electric current, not shown, to one post of the switch 90 and a conductor wire 93 leads from the other post thereof to the solenoid 52. A return or ground conductor wire 94 leads from the solenoid 52 back to a suitable ground, not shown, of the source of electric current. The switch 90 may be of any suitable construction and which is normally open to interrupt the circuit to the solenoid 52. An arm 95 projects outwardly from the switch 90 and is adapted to be pivotally mounted to swing downwardly, when pressure is applied thereto, for closing the switch 75

and when released is adapted to return to its raised position for again opening the switch. Any conventional construction of switch possessing these features may be employed, as no claim is made to the switch, per se.

A crank 96 is provided with a hub 97 which is turnably mounted on the shaft 14 and which is disposed between collars 98, which are secured to the shaft 14, for preventing the crank 96 from sliding longitudinally thereof. As best seen in Figure 3, the arm of the crank 96 is provided with a straight, radially projecting forward edge and a rounded, cam shaped back edge. A crank 99 is provided with a hub portion which is adjustably keyed to the shaft 14 by a set screw 100 and which is disposed adjacent to the crank 96. A stud or pin 101 projects laterally from the arm of the crank 99, adjacent its free end, and is arranged to engage against the rounded, back edge of the crank 96. It will thus be obvious that the crank 99, as it turns in a counterclockwise direction, as seen in Figure 3, with the shaft 14, will engage the back edge of the crank 96 to swing it upwardly from a depending position slightly past an upright position, or slightly past the position as seen in Figure 3, after which the crank 96 will be swung downwardly in a counterclockwise direction by gravity back to a depending position. The lever 95 of the switch 90 is disposed in the path of the arm of the crank 96 to be engaged thereby during its downward swing so that the lever 95 will be swung downwardly thereby to momentarily close the switch 90 for closing the circuit to the solenoid 52.

The circuit by thus being closed will momentarily energize the solenoid 52 to cause it to function in a conventional manner as a magnet to draw the core 56 downwardly. The core 56 in moving downwardly will function as a plunger. The sharpened end 58 will be moved downwardly through the lower end of the bore 45 and in passing through the tape 24 will cut a piece therefrom corresponding to the shape of the lower end 58 and will carry this piece of tape 102 downwardly through the lower end of the bore 45 and apply it to the warp 20, as seen in Figure 4. An opening 103 will thus be formed in the tape 24, as seen in Figure 7, which, however, is not sufficiently wide to weaken the tape 24 sufficiently so that it cannot continue to be wound onto the roller 37. As previously pointed out, the portion of the tape which is cut out to form the piece 102 will have been just previously moistened on its coated side by the roller 65 so that it will readily adhere to the warp 20. After the solenoid 52 is deenergized the springs 60 will react to return the core or plunger 56 to a raised position, ready for another downstroke when the solenoid 52 is again energized. Between the downstrokes of the core 56, the lever 82 is rocked outwardly by the cam 78 engaging the lever 83, as previously explained, to move the levers 82 and 71 to the positions, as seen in Figure 2, so that when the cam 78 rides under the free end of the lever 83 the spring 89 can react to draw the lever 82 inwardly for exerting a push on the connecting rod 87 to turn the lever 71 and the ratchet wheel 70 approximately a quarter of a turn in a clockwise direction. This will advance the tape 24 toward the roller 35 to position another portion of the tape beneath the cutter 58 to be cut by the next stroke of the core 56. The roller 35 is provided with the felt periphery 36 for frictionally engaging

the tape and said periphery also frictionally and yieldably engages the roller 37 to cause it to turn in the opposite direction to the roller 35 for winding the tape 24 thereon. From time to time the set screws 42 may be loosened to allow for the tape being wound on the roller 37 and so that said roller can be moved slightly away from the roller 35.

The cut marker shaft 14 revolves very slowly and it will be apparent that the mechanism, previously described, can be adjusted by adjusting the cam 78 by the set screw 79 and the crank 99 by its set screw 100 to cause the parts, previously described, to be operated at the desired time during each revolution of the shaft 14, which also functions to operate a conventional cut marking means, not shown, of the slasher 12 which applies a mark, by means of dye to the warp 20.

Referring to Figure 5, 104 designates a portion of the forward drop wire rod of a loom, not shown, 105 designates generally a portion of the rear drop wire rod thereof, and 106 designates generally a drop wire which is mounted on the rod 105 and which is of conventional construction and mounted in its conventional manner on the rod 105. These parts, 104, 105 and 106, form conventional portions of a loom, not shown, and are adapted to function in conjunction with a feeler, designated generally 107 and comprising another part of the invention 16. The feeler 107 includes a length of wire 108 one end of which is passed through the elongated slot 109 in the drop wire 106. Said end 110 is then turned back upon itself and extends back through the opening 111 which is formed in the drop wire 106 below its slot 109. The rod 105 extends through the slot 109, in a conventional manner.

Adjacent the opposite end of the length of wire 108 a stop member 112 is attached thereto through which the length of wire 108 extends and said last mentioned end 113 of the wire length 108 depends downwardly from the stop member 112. Intermediate of the ends of the length 108, a hook 114 is slidably connected thereto and projects upwardly therefrom and engages over the forward rod 104 for supporting the feeler 107. A collar 115 is fixed to the length 108, between the hook 114 and the member 112. An expansion coil spring 116 is mounted on the strand 108, between the hook 114 and the collar 115 for urging the strand 108 forwardly or away from the drop wire 106.

The strand 108 is supported by the hook 114 so that the forward end 113 of the strand extends through two of the threads of the warp 20, which threads support the piece of tape 102. The member 112 is provided to prevent the strand end 113 from dropping too far down through the warp 20. The spring 116 is only of sufficient strength to hold the strand 108 in its normal position, as seen in Figure 5, so that when the piece of tape 102 engages the end 113 it will force the feeler member 107 rearwardly so that its hooked end 110 will disengage the opening 111 thereby allowing the drop wire 106 to drop relatively to the drop wire rod 105 and into the conventional stop mechanism, not shown, of the loom for stopping the loom.

From the foregoing it will be apparent that the invention will operate automatically for applying a piece of tape to the warp as it passes through a slasher and at a definite position on the warp relatively to the cut mark made by the cut marker. When the warp then passes

through a loom the piece of tape 102 will stop the loom when the cut mark and the tape have reached certain positions in the loom, thus affording automatic means for stopping the loom and avoiding the necessity of having to have the loom watched for the cut mark on the warp.

Various modifications and changes are contemplated and may obviously be resorted to, provided they fall within the spirit and scope of the invention as hereinafter defined by the appended claims, as only a preferred embodiment of the invention has been disclosed.

I claim as my invention:

1. On attachment for textile machines comprising a frame mounted on a slasher, transversely thereof, said slasher having a sheet of warp threads passing therethrough, means for mounting a roll of tape at one end of said frame, the tape being provided with an adhesive on one side thereof, a roller mounted in the opposite end of the frame and on which the free end of the tape is wound, a plunger mounted on said frame intermediate of its ends and arranged to move vertically, said plunger having a cutter on its lower end, an opening in said frame through which the plunger moves on its down stroke, said tape being arranged to move over said opening to be engaged by the plunger on its down stroke for cutting a piece from the tape, and a solenoid disposed around the upper portion of the plunger for drawing the plunger downwardly, when the solenoid is energized, said frame being disposed above and adjacent the warp and arranged so that the piece of tape cut from the roll by said plunger will be applied by the plunger to threads of the warp.

2. An attachment as in claim 1, comprising spring means for returning the plunger to a raised position, when the solenoid is deenergized.

3. An attachment as in claim 1, comprising a roller journaled in said frame and over which the tape moves before reaching the opening in said frame, and a receptacle in the frame into which the roller extends and which is adapted to contain water for wetting the roller so that the tape will be moistened on its coated side by contact with the roller.

4. An attachment as in claim 1, comprising means for intermittently advancing the tape including pawl and ratchet means for turning said roller, a lever pivotally mounted intermediate of its ends, a cam keyed to the cut marker shaft of the slasher for engaging one end of said lever for rocking the lever in one direction, a link connected at one end to the opposite end of said lever and connected at its opposite end to the pawl and ratchet means for swinging the pawl in one direction, and means for moving said lever in the opposite direction for swinging said pawl in the opposite direction for actuating the pawl and ratchet means.

5. An attachment as in claim 1, comprising a lever loosely mounted on the cut marker shaft of the slasher, a second lever keyed to the cut marker shaft and having a lug for engaging the first mentioned lever for moving it from a depending to past an upright position, said first mentioned lever being moved by gravity from an upright to a depending position, and a normally open switch interposed in the circuit of the solenoid and arranged to be engaged and momentarily closed by the first mentioned lever while moving from an upright to a depending position.

6. An attachment as in claim 1, comprising a

feeler wire having a hook near its forward end for engaging the front drop wire rod of a loom, said feeler wire having a hook at its rear end adapted to engage and support a drop wire, the forward end of the feeler wire extending through certain of the threads of the warp and being disposed to be engaged by a piece of tape applied to the warp so that the feeler wire will be moved rearwardly, by engagement with the tape, for disengaging its hooked end from the drop wire to permit the drop wire to move downwardly for stopping the loom.

7. An attachment as in claim 1, comprising means mounted on a loom and arranged to be engaged by the tape on the warp passing through the loom for releasing the stop mechanism of the loom for stopping the loom when the tape, carried by the warp, reaches a certain position in the loom.

8. A warp marker attachment for textile machines comprising a frame member adapted to be mounted on a slasher above and adjacent the warp passing therethrough, said slasher having a cut marker shaft driven by the slasher, adhesive tape carried by said frame member, means adapted to be connected to and actuated by the cut marker shaft of the slasher for advancing the tape, an electrically actuated cutting member for cutting a piece from the tape and for applying the cut piece of tape to the warp, and means actuated by the cut marker shaft for momentarily closing the circuit for actuating said cutter.

9. An attachment as in claim 8, said means for advancing the tape including a bearing stand at one end of the frame member, a roller journaled in said bearing stand and on which one end of the tape is wound, a shaft projecting from

the bearing stand and journaled therein, a ratchet wheel keyed to said shaft, a lever pivotally mounted intermediate of its ends on said shaft, a pawl on one end of said lever for engaging the teeth of the ratchet wheel for turning the ratchet wheel when the lever is turned in one direction and for riding over the teeth of the ratchet wheel when the lever is turned in the other direction, gear means connecting the shaft of the ratchet wheel to said roller, a lever pivotally mounted on a side of the slasher, a link connected at one end to one end of said last mentioned lever and pivotally connected at its opposite end to the opposite end of said first mentioned lever, a cam keyed to the cut marker shaft of the slasher for engaging the opposite end of said last mentioned lever for turning the first mentioned lever in one direction, and spring means for actuating the last mentioned lever for moving the first mentioned lever in the other direction.

10. In combination with a slasher having a sheet of warp threads passing therethrough and provided with a driven cut marker shaft, a frame mounted on the slasher over the warp, a roll of adhesive tape carried by the frame, means connected to and intermittently actuated by the cut marker shaft for moving the tape, an electrically actuated plunger mounted in the frame and above a portion of the tape, and means connected and intermittently actuated by the cut marker shaft and adapted to close a circuit to actuate the plunger, and said plunger being constructed and arranged, when actuated, to move downwardly to cut a piece from the tape and to apply the piece to the warp threads.

GEORGE B. McCOMBS.
